UNITED STATES PATENT OFFICE.

GEORGE D. HENRY, OF KANSAS CITY, MISSOURI, ASSIGNOR TO SWIFT FLY SWATTER MANUFACTURING COMPANY, OF KANSAS CITY, MISSOURI, A CORPORATION OF MISSOURI.

WIRE-BENDING MACHINE.

1,194,498.

Specification of Letters Patent. Patented Aug. 15, 1916.

Application filed May 10, 1915. Serial No. 27,176.

To all whom it may concern:

Be it known that I, GEORGE D. HENRY, a citizen of the United States, residing at Kansas City, in the county of Jackson and 5 State of Missouri, have invented certain new and useful Improvements in Wire-Bending Machines; and I do declare the following to be a full, clear, and exact description of the invention, such as will enable others skilled 10 in the art to which it appertains to make and use the same, reference being had to the accompanying drawings, and to the figures of reference marked thereon, which form a part of this specification.

15 My invention relates to a wire-bending device, and more particularly to a device for use in forming wire handles; the principal object of the present invention being to provide means for bending a ring at one end of 20 the handle and turning the free end of the ring about the handle body to maintain the shape of the ring and form a strong, substantial and slightly structure. In accomplishing this object I have provided im- 25 proved details of structure, the preferred forms of which are illustrated in the accompanying drawings, wherein:—

Figure I is a perspective view of a wire-bending machine containing my improvements. Fig. II is a central vertical section of the same, partly in elevation. Fig. III is an enlarged detail perspective of a part of the device, particularly illustrating the handle trough and ring-forming parts. 35 Fig. IV is a detail perspective, particularly illustrating the tying parts. Fig. V is a plan view of the ring end of a handle, as it appears when the handle is removed from the bending device.

40 Referring more in detail to the drawings: 1 designates a platform upon which the device is mounted, 2 a table which is supported above the platform by posts 3, and 4 a cover plate, which is supported above 45 the table by posts 5. Rising from the platform 1, adjacent the table, is a standard 6 having a bearing 7 at its upper end at an elevation slightly above that of the table and which is provided with a top slot 8 that 50 is preferably beveled in order to facilitate the placing of a wire handle shank therein. Revolubly mounted in the bearing 7 is a work holder comprising a shaft 10 having a longitudinal groove therein that is adapt-

ed for registering with the bearing groove 55 and has its base at the center of the shaft so that the shaft may revolve about a handle body that is located in the groove and held at one end by a shaping element. The shaft body has extensions at opposite ends 60 of the bearing, but is anchored to the bearing by collars 11 that are fixed on the shaft and bear against opposite ends of the bearing to provide for free rotatable movement of the shaft while preventing longitudinal move- 65 ment thereof. Fixed to the outer end of shaft 10 is a crank handle 12 and fixed on the inner end thereof, closely adjacent the table 2, is a block 13 of substantially greater diameter than the shaft; the said block be- 70 ing semicircular and having an open groove 14 coextensive with the groove 15 in the shaft. Fixed on the inner end of the block 13, at one side of the groove, is a hook 16, the lip 17 of which overlies and is spaced 75 from a flat face of the block in order that a wire, that forms a projection of the handle body, may be projected between the block and lip and nested in the lip, for the purpose presently described. The table 2 80 has an aperture 19 near its edge adjacent the shaft block 13, and slidably mounted in said aperture and slidably guided over a post 20, that is fixed to and rises from the platform 1, is a hollow plunger 21 having 85 a closed upper end 22; the hollow plunger being yieldingly held upwardly by a spring 23 that is housed within the plunger and bears against the closed end 22 and against the top of the guiding post 20, to 90 serve as a shaper about which one end of the handle is turned to the desired shape. The upper projection of the plunger 21 is limited by a crank block 24, which is rotatably mounted in the cover plate 4 and held 95 against vertical movement therein by upper and lower collars 25 and 26 that are fixed to the block and lie at opposite sides of the cover plate; the upper portion of the block being provided with a crank handle 100 27 and the lower portion with a crank mem- 105 ber 28 having a depending pin 29 at its outer end that projects along the inner edge of an arcuate rib 30 on plate 2 and concentric with the plunger and the crank block 24.

31 designates a wire handle member hav- 105 ing projecting ends 32 and 33; the end 33 be-

ing of substantially greater length than the end 32 in order that it may be shaped in the present machine to form the loop 34 (Fig. V).

5 As a convenient means for lowering the plunger 21, I provide the same with a lever 35 which is pivotally mounted on a standard 36 and has a yoke 37 at one end pivotally mounted on the plunger; the opposite end of the lever being projected beyond the table where it can be easily manipulated.

In using the device, presuming the parts to be constructed and assembled as described, the handle 31, which has previously 15 been twisted, is seated in the shaft groove through the bearing slot 8, so that the ends 31 and 33 project from the ends of the grooved head 13, with the long end of the wire lying on the rib 30 on the table 2. With 20 the parts so arranged, the crank handle 27 is rotated to bring the crank pin 29 into engagement with the long end of the wire; the engagement of the arm with the wire and rotation of the arm causing the latter to 25 bend the end of the wire about the plunger 21 to form the loop and project the end of the wire beneath the hook 17; the arm 29 traveling close to the plate 30, so that the wire is held against vertical displacement 30 that might tend to bend the ring at an incline relative to the plunger. When the loop has been formed and the end of the wire projected beneath the hook, the crank handle 12 is rotated to turn the shaft in its bearing and rotate the block 13. Rotation 35 of the block 13 causes the hook 17 to engage the end of the wire loop and turn said end about the body of the handle so that the end of the wire is tied to the handle to maintain 40 the loop; rotation of the shaft causing the same to turn about the handle body without affecting the handle, owing to the location of the handle at the center of the shaft. When the loop has been tied, as described, 45 the plunger is lowered against the tension of its spring to release the loop, which has been formed thereabout, so that the handle may be removed from the plunger and the grooved shaft; the plunger returning automatically to normal position as soon as 50 pressure is removed from the shipper lever 35, so that it is in condition for a succeeding operation. By arranging the bearing 7 at a slight incline to the table 2, the wire is 55 sprung as the loop is being formed, and the arm 33 pressed against the bearing plate 30, to insure its bending in the proper place.

Having thus described my invention, what I claim as new therein and desire to secure 60 by Letters-Patent is:

1. The combination with a wire holder, of a table, a plunger in the table, and a crank arm arranged for engaging a projecting end of a wire carried in said holder and turning 65 the same about the plunger.

2. The combination with a wire holder, of a table, a plunger in the table, a crank arm arranged for engaging a projecting end of a wire carried in said holder and turning the same about the plunger, and means for withdrawing the plunger to free the wire. 70

3. The combination with a wire holder, of a plunger, a crank arm concentric with and extending along the plunger, and means for actuating the crank arm. 75

4. The combination with a wire holder, of a plunger, a crank arm concentric with and extending along the plunger, means for actuating the crank arm, and means for moving the plunger away from the crank arm. 80

5. The combination with a wire holder, of a table having a curved bearing rib thereon, a plunger in said table concentric with the rib, a rotatable crank arm having its end projected along the rib, and means for rotating 85 the crank arm.

6. The combination with a wire holder, of spaced upper and lower table members, a crank block rotatable in the upper table member, a depending arm on said block, a plunger movable in the lower table member, yielding means for retaining the plunger 90 against the crank block, and means for actuating the plunger.

7. The combination with a bearing having 95 a longitudinal slot, of a shaft revolvably mounted in the bearing and having a longitudinal groove, a hooked lip on the shaft at one side of the groove, and means for forming a loop on a member held in the shaft and 100 projecting said member beneath the hooked lip.

8. The combination with a wire holder, of a rotatable crank block, a depending arm on 105 said block, a post located adjacent the block, a hollow plunger slidably mounted on the post and adapted for engaging the block, a spring within the plunger and bearing against the post and plunger to urge the plunger toward the block, means for moving 110 the plunger against the tension of said spring, and a wire holder adapted for co-operation with the plunger and crank arm.

9. The combination with a shaft having an opening at its longitudinal center, of means for rotating the shaft about a body located in the opening, and means operable by the shaft for turning a member about the body. 115

10. The combination with a shaft having 120 a seat along its longitudinal center, of a shaper member at one end of the shaft, means for turning a member of a handle located in the shaft seat about the shaper member, means for rotating the shaft, and 125 means on the shaft for engaging said member and turning the same about the body when the shaft is rotated.

11. The combination with a bearing having 130 a longitudinal slot, of a shaft rotatably

mounted in the bearing and having a longitudinal groove with a seat at the diametrical center of the shaft, a block at one end of the shaft having a flat face and an open groove 5 coextensive with the shaft groove, whereby a handle body may lie in the grooves concentrically with the shaft and block, a shaper member adjacent the end of the extension, means for turning a projecting end 10 of a handle about the shaper member over onto the block while the handle body is seated in said grooves, means for rotating the shaft and block about the held handle body, and a hook on the block for holding the 15 shaper member to the end of the handle body

and turning the same about the handle body when the shaft and its block are rotated.

12. The combination with a bearing having a longitudinal slot, of a shaft rotatable in the bearing and provided with a longitudinal groove, a head block on one end of the shaft having a groove coextensive with the shaft groove, a lip on said head at one side of the groove, means for rotating the shaft, a plunger arranged adjacent the head 20 block, a crank member having an arm rotatable about the plunger, and means for actuating the plunger.

In testimony whereof I affix my signature.

GEORGE D. HENRY.
